UNITED STATES PATENT OFFICE.

JAMES F. THOMAS, OF CLARINDA, IOWA.

GARMENT-PRESSING DEVICE.

1,352,158.

Specification of Letters Patent. Patented Sept. 7, 1920.

Application filed January 2, 1919. Serial No. 269,241.

To all whom it may concern:

Be it known that I, JAMES F. THOMAS, a citizen of the United States, residing at Clarinda, in the county of Page and State 5 of Iowa, have invented certain new and useful Improvements in Garment-Pressing Devices; and I do declare the following to be a full, clear, and exact description of the invention, such as will enable others skilled in 10 the art to which it appertains to make and use the same.

My invention relates to that class of devices intended to be clamped upon the creases of trousers, coat sleeves, etc., to press the 15 same, and the principal object is to provide a foldable and adjustable electrically heated device of this class which will thoroughly crease the garment by strong spring pressure while such garment is clamped therein.

20 In carrying out the above object, a further object is to provide a device which may fold compactly when not in use, thus permitting the device to be conveniently carried or placed in a small space when not required.

25 A still further object is to provide a device of the class described which may be folded while a pair of trousers are in the pressing clamps without injury to the garment.

Yet another object is to provide auxiliary 30 clamps at the ends of the main clamps, adapted to hold the cuffs of the trousers before said main clamps are closed on the creases, thus permitting the garment to be drawn taut to remove all wrinkles.

35 Another object is to provide an adjustable bar and link arrangement whereby the trousers are held so stretched as to prevent wrinkling and to remove any wrinkles which may exist when the device is applied to the garment, and to render the device adjustable for 40 different sizes of garments.

A still further object is to construct the clamps with strong pressure so that the garments may be thoroughly creased, and to 45 provide a simple and efficient means of pressing them at any time and in a very simple manner.

An additional object is to construct the clamps in a simple and inexpensive, yet in a 50 highly efficient manner, said clamps being so made as to cause them to remain open when applying the device to the garment.

Yet another object is to provide linings of 55 pressing twill or the like for the pressing clamps, so that moistening of these linings will assist in creasing the garment, said lin-

ings also insuring antislipping engagement of the clamps with the garment.

A still further object is to provide a press which, by simply removing its lower section, 60 is adaptable for pressing coat sleeves, provision being made for heating the upper section of the press when pressing sleeves and for heating both sections when pressing trousers.

With the foregoing objects in view, the invention resides in the novel features of construction, and unique combinations of parts to be hereinafter fully described and claimed, the descriptive matter being supplemented 70 by the accompanying drawings which form a part of this specification and in which:

Figure 1 is a side elevation of the invention applied to a pair of trousers.

Fig. 2 is a side elevation showing the device folded.

Fig. 3 is a vertical section on the plane of the line 3—3 of Fig. 1.

Fig. 4 is an elevation of the side of the device opposite that shown in Fig. 1.

Fig. 5 is a horizontal section on the plane of line 5—5 of Fig. 1.

Fig. 6 is a detail end elevation showing the manner in which the clamps remain open until closed by hand.

Fig. 7 is a detail perspective view showing more particularly one of the auxiliary clamps.

Fig. 8 is a side elevation of one of the electric heaters and a portion of the other 90 which coats therewith, the several parts being separated from each other.

Fig. 9 is a longitudinal section of the parts seen in Fig. 8, in the same relative positions.

Fig. 10 is a view similar to Fig. 9, but 95 showing the several parts operatively associated.

Fig. 11 is a transverse section on the plane of line 11—11 of Fig. 9, showing the open position of the switch.

Fig. 12 is a detail longitudinal section through part of the connecting means of the two sections of the heater, showing the switch closed.

Fig. 13 is a transverse section on the plane 105 indicated by line 13—13 of Fig. 12, showing the closed position of the switch.

Fig. 14 is a diagram of the heaters as used for pressing trousers.

Fig. 15 is a view similar to Fig. 14, showing only the upper sections of the heaters as used when pressing coat sleeves.

In the drawings above briefly described, the numerals 1 have reference to a pair of elongated clamps to receive therein the front and rear creases of a pair of trousers, each 5 of said clamps being formed of leaves 2 which are shown constructed of sheet metal.

Each clamp 1 is formed of an upper section U and a lower section L and the leaves 2 at the rear side of the clamps are detachably connected by bifurcated lugs 3 and clamping bolts 4 which the furcations of said lugs straddle, the lug of each clamp being carried by one section thereof and the bolt by the other. These bolts are provided with 10 wing or other suitable hand releasable nuts so that the connection between the two sections U—L of the clamps may be easily released to permit folding of said clamps one upon the other for carrying in a suit case or 15 the like, either with or without the garment clamped therein. When the device is to be folded with the trousers clamped therein, the sections U and L are first separated to permit the trousers to act as the hinge without 20 in any manner stretching the material.

For forcing the two clamps 1 away from each other after they are applied to the creases, and for adjusting the distance between said clamps according to the size of 25 the garment, upper and lower pairs of toggle links 5 and 5' are provided, the outer ends of said links being pivoted at 6 to the rear leaves of said clamps. The inner ends of the links 5' are pivoted at 6' to the lower ends 30 of upper and lower bars 7 and 7' located between and substantially parallel with the clamps, and the inner ends of the links 5 are pivotally connected by clamping bolts 8 which extend through longitudinal slots 8' 35 in said bars 7 and 7'. By this bar and link arrangement, the device may be held in extended position upon all sizes of garments or 40 may be folded compactly as shown in Fig. 2.

At the lower ends of the clamps 1, auxiliary clamps 1' are provided, said auxiliary clamps being formed by transplitting one leaf of each clamp 1 and being adapted to grip the cuffs of the trousers before said clamps 1 are closed upon the front and rear 45 creases of the trouser legs. By this means the legs may be so stretched as to move all wrinkles therefrom before the clamps 1 are closed.

Although any preferred means could well 50 be employed for connecting the leaves 2 of each clamp 1, the outer edges of said leaves are preferably stamped so as to form respectively a longitudinal, relatively large groove 9 and a longitudinal, comparatively 55 small rib 10 in said groove to constitute a hinge upon which the two leaves may rock, C-shaped springs 11 being clipped around said outer edges of the leaves as shown most clearly in Fig. 5. The springs 11 not only 60 serve to retain the grooves and ribs in opera-

tive relation, but act to hold the clamps tightly closed to effectively crease the trousers by strong spring pressure. The front leaves of the clamps are by preference provided on their inner edges with finger pieces 70 12 whereby they may be easily opened.

Fig. 6 discloses more clearly than the other views, the grooved and ribbed portions 9 and 10 respectively of the leaves 2, these portions being so constructed as to cause the tension of 75 the springs 11 to hold the clamps opened until closed by hand. It is the engagement of the hooked edge 10' of the ribbed portion 10 with the groove edge 9', caused by the tension of the springs 11, that causes the 80 clamps to remain open.

In most cases, strips of pressing twill, felt or the like 13 will be cemented or otherwise secured to the inner faces of the several leaves 2, in order that they may effectively 85 grip the garment. Also, dampening of these strips assists materially in creasing the trousers, the necessary heat being furnished by the electric heaters described below.

Within the hollow rib 10 of each clamp 1, 90 an electric heater is provided, each of said heaters consisting of an upper section U' and a lower section L' carried respectively by the sections U and L of the clamp. The sections of the heaters are constructed and 95 connected in a novel manner, so as to permit the entire pressing device to be heated for pressing trousers, or to heat only the upper sections of the clamps when they are to be used for pressing coat sleeves, the lower sections having been removed by loosening of 100 the bolts 4. Since the structure of both heaters is the same, only one will be described in detail, and to this end reference may be made to Figs. 8 to 13.

The upper heater section U' includes a tubular casing 20, preferably of insulation, a block of insulation 21 secured in the upper end of said casing, a second insulating block 22 anchored in the lower end 110 of said casing, a pair of socket members 23 carried by said block 21, a pair of connecting pins 24 mounted in and projecting outwardly from said block 22, a heating coil 25 in the casing 20 connecting one of 115 said socket members with one of said pins, and a wire 26 connecting the other socket member and pin.

Pins 27 carried by a coupling member 28 are adapted for reception in the socket members 23 and feed wires 29 lead to said pins and branch from the well known form of cable 30, which, as seen in Figs. 1, 2 and 4, may be provided with a plug 31 for reception in a lamp socket or other electric current 120 supply means.

The lower heater section L' consists of a casing 20', an insulating block 21' in the upper end of said casing, a pair of socket members 23' carried by said block, a heating 125

coil 25' connected to one of said socket members, and a wire 26' leading from said coil to the other socket member. The socket members 23' are adapted to receive the pins 5 24 when the entire press is to be used, as when pressing trousers, and the current will then flow through both coils 25 and 25', which will cause said coils to furnish the required amount of heat to effectively press 10 the trousers while they are held by the strong spring pressure of the clamps. When only the upper sections U of the clamps are to be used, as when pressing coat sleeves, the bolts 4 are loosened and the lower sections 15 L removed, the pins 24 then moving from the socket members 23'. Some means are now necessary to bridge the gap between the aforesaid pins 24, in order that the current may travel through the coil 25 and back by 20 way of wire 26. This could be accomplished in numerous ways but I have preferably provided the switch described below.

An insulation block 32 is secured in the lower end of casing 20 and abuts the outer 25 end of block 22, said block 32 having in its inner end a socket 33 and being provided with a bore 34 extending from said socket to the outer end of the block. A stem 35 is rotatable in the bore 34 and carries a cylindrical head 36 located in the socket 33, said head having a bridge plate 37 secured on its periphery as seen for instance in Figs. 9, 10, 11 and 12. The bridge plate 37 is adapted, when the current is to pass only 35 through the upper heating coil, to be turned to the position of Figs. 12, 13 and 15 so that it contacts with both pins 24 and bridges the gap between them as above mentioned.

When the current is to pass through both 40 coils 25 and 25', the switch is turned by means of the stem 35, to the position depicted in Figs. 9, 10, 11 and 14, so that the plate 37 clears one pin 24 and does not therefore conduct current from one pin to the 45 other. The stem 35 may project sufficiently to be turned by the thumb and fore finger and is preferably provided with a kerf 38 which may receive a knife point or the like if it should be desirable to use such an instrument for turning the switch.

In use, the two clamps are separated the required amount by distending the links 5 and 5', said clamps being then applied to the front and rear creases of the trousers, 55 taking care that the clamps 1' be first applied so that the garment may be stretched before the clamps 1 are closed. After applying the clamps in this manner, the bar and link arrangement 7-7'-5-5', is set 60 to hold the two clamps spaced apart sufficiently to prevent wrinkling of the garment. A hook 14 may be provided if desired for supporting the device when extended with a pair of trousers therein.

65 Whenever required, the upper and lower

sections of the device may be disconnected and folded compactly for carrying in a suitcase or the like, or if required said sections may be folded one upon the other while the trousers are clamped therein, it being first necessary however, to separate said sections sufficiently to permit the garment to act as a hinge.

From the foregoing, it will be seen that although the invention is of simple and inexpensive nature, it will be useful and convenient to operate. Since probably the best results are obtained from the several details shown and described, these details are preferably used, but within the scope of the invention as claimed, numerous minor changes may well be made.

I claim:

1. A garment press comprising a crease clamp consisting of two leaves hinged together at one edge and means for holding said leaves closed, and electric heating means for said leaves extending along the hinged edges thereof.

2. A garment press comprising a pair of sheet metal leaves stamped at one edge to form a hollow bead on one and a groove for the other, said groove receiving said bead to hingedly connect the two leaves, an electric heater in and extending throughout the length of said hollow bead, and means for tightly holding said leaves closed upon the garment.

3. A garment press comprising a crease clamp formed of two sections abutting end to end and means for detachably connecting said sections, electric heating coils carried one by each section of said clamp, wiring connected to one of said coils for supplying the current, coil connecting means for completing the circuit of the coils when the two clamp sections are connected and for breaking said circuit when said sections are disconnected, and means for completing the circuit of said one coil when the other is disconnected therefrom.

4. A garment press comprising a crease clamp formed of two sections abutting end to end and means for detachably connecting said sections, electric heating coils carried one by each section of said clamp, wiring connected to one of said coils for supplying the current, a pair of terminals for each coil positioned at the inner ends of said clamp sections, the terminals of one coil coacting with those of the other to complete the circuit of said coils when said sections are connected, and means for bridging between the terminals of said one coil when the other is disconnected therefrom.

5. A garment press comprising a crease clamp formed of two sections abutting end to end and means for detachably connecting said sections, electric heating coils carried one by each section of said clamp, wiring

- connected to one of said coils for supplying the current, a pair of terminals for each coil positioned at the inner ends of said clamp sections, the terminals of one coil coacting with those of the other to complete the circuit of said coils when said sections are connected, an insulator from which the terminals of said one coil project, said insulator having a recess between said terminals and a bore parallel with said terminals leading from said recess to the outer end of the insulator, a stem rotatable in said bore and having a head located in said recess, and a bridge plate mounted on said head and adapted to bridge between said terminals of the one coil when the other coil is disconnected therefrom.
6. A trousers pressing device comprising a pair of clamps for the creases, upper and lower pairs of toggle links pivoted at their outer ends to said clamps, a longitudinal bar between said clamps having a longitudi-
- 10
- 15
- 20

nal slot at one end, a pivotal connection between the inner ends of one pair of links and the unslotted end of said bar, and a 25 clamping bolt pivoting the inner ends of the other pair of links to said bar, said bolt passing through said slot.

7. A trousers pressing device consisting of a pair of metal strips, one strip having a 30 longitudinal groove stamped in one edge and the other strip having its corresponding edge stamped to form a longitudinal rib received in said groove, and C shaped clamps clipped around said edges of the 35 strips for exerting strong pressure to thoroughly crease the garment, the ribbed edge of the one leaf having a longitudinal hook flange to engage the inner edge of the groove of the other leaf, whereby to hold the leaves 40 open until closed manually.

In testimony whereof I have hereunto set my hand.

JAMES F. THOMAS.
